UNITED STATES PATENT OFFICE.

FRANKLIN YATES, OF RACINE, WISCONSIN.

SASH HOLDER AND FASTENER.

SPECIFICATION forming part of Letters Patent No. 633,937, dated September 26, 1899.

Application filed June 1, 1898. Serial No. 718,988. (No model.)

To all whom it may concern:

Be it known that I, FRANKLIN YATES, a citizen of the United States, residing at Racine, in the county of Racine and State of Wisconsin, have invented certain new and useful Improvements in Sash Holders and Fasteners; and I do hereby declare the following to be a full, clear, and exact description of the invention, such as will enable others skilled in the art to which it appertains to make and use the same.

This invention relates to sash holders and fasteners, the object in view being to provide a combination sash holder and fastener which is extremely simple in construction, reliable in operation, and which will sustain the sash at any desired elevation and by means of which the sash may be securely locked when closed.

The detailed objects and advantages of the invention will appear in the course of the subjoined description.

The invention consists in a combined sash holder and fastener embodying certain novel features and details of construction and arrangement of parts, as hereinafter fully described, illustrated in the drawings, and incorporated in the claim.

In the accompanying drawings, Figure 1 is a front elevation showing a sufficient portion of a window frame and sash to illustrate the application thereto of the improved sash holder and fastener. Fig. 2 is a detail vertical section through the casing of the device, showing the keeper-spring and operating devices. Fig. 3 is a detail perspective view of the cam. Fig. 4 is a similar view of the spring-keeper.

Similar numerals of reference designate corresponding parts in all of the figures.

In the drawings, 1 designates a window-frame, and 2 a sash. To the inner face of the sash is applied a metal casing 3, closed at top and bottom, as indicated at 4, and open on one side, as at 5, next to the window-frame. The opposite side of the casing is closed, as at 6. The casing is also provided with oppositely-extending and vertically-disposed ears 7, having openings 8 for the reception of suitable fasteners, whereby the casing is securely and rigidly attached to the window-sash.

Near the lower portion of the casing the

latter is provided with a laterally-projecting bevel-faced lip or catch 9. This catch cooperates with a bow-shaped keeper 10, which is constructed of a piece of flat spring material, the ends of which lie in substantially the same plane, one end being provided with an opening 11 for the reception of a suitable fastener 12, which passes into the window-frame, and the other end having a longitudinal slot 13, through which passes a fastener 14, said slot permitting the end of the spring-keeper to move sufficiently to allow the spring to be flattened against the window-frame for releasing the catch 9. The central portion of the keeper is bowed, as shown at 15, and provided with an opening 16, into which the lip or catch 9 snaps when the sash is in its lowermost position. By pressing the keeper 10 against the window-frame it is moved out of engagement with the catch 9, so as to allow the window-sash to be raised. The catch 9 and the keeper 11 constitute the means for locking the sash closed.

17 designates a cam which is pivotally mounted at 18 within the casing. This cam is provided with a peripheral groove in which is seated a segmental shoe 19, of rubber, designed to frictionally engage the window-frame. On each side of the shoe and cam segmental plates 20 are secured for retaining the shoe 19 in place. The pivot of the cam is in the form of a spindle 21, which is rigidly connected with the cam and journaled in the casing. The spindle projects through the casing and is provided upon the inner surface of the sash with a handle or button 22, by means of which the cam may be turned for moving it out of engagement with the window-frame.

By means of the construction above described and the particular disposition of the cam the sash may be freely lifted to any desired point, whereupon the cam frictionally engages the window-casing and operates with a wedging action against the frame, the tendency being to swing the cam farther outward and cause it to bind still more firmly against the window-frame, thereby securely holding the sash and preventing it from falling. When it is desired to lower the sash, the spindle is turned in the opposite direction, which will swing the cam out of engagement with

the window-frame. The sash may now be readily lowered, and when it has reached its lowermost position the catch 9 snaps into engagement with the spring-keeper 10, and the sash is thus fastened or locked and prevented from being raised from the outside. At the same time the spring-keeper 10 may be readily pressed inward or flattened against the window-frame by the operator inside of the window when it is desired to release the sash and allow it to be raised.

Having thus described the invention, what is claimed as new, and desired to be secured by Letters Patent, is—

15 A combined sash holder and fastener com-

prising a casing, a cam pivotally mounted therein and having a groove in its periphery, a segmental rubber shoe seated in said groove, an operating-spindle connected rigidly to the cam and journaled in the casing, a lip or catch 20 projecting laterally from the casing, and a bow-shaped spring-keeper applied to the window-frame and adapted to be engaged by said lip or catch.

In testimony whereof I affix my signature 25 in presence of two witnesses.

FRANKLIN YATES.
